UNITED STATES PATENT OFFICE.

WILLIAM H. KING AND HERBERT B. TAYLOR, OF NEWARK, NEW JERSEY.

DESIGN FOR A CASE FOR WAGE-CALCULATING MACHINES.

SPECIFICATION forming part of Design No. 27,398, dated July 20, 1897.

Application filed April 27, 1897. Serial No. 634,177. Term of patent 7 years.

To all whom it may concern:

Be it known that we, WILLIAM H. KING and HERBERT B. TAYLOR, citizens of the United States, residing at Newark, in the county of 5 Essex and State of New Jersey, have invented and produced a new and original Design for a Case for Wage-Calculating Machines; and we do hereby declare the following to be a full, clear, and exact description of the invention, 10 such as will enable others skilled in the art to which it appertains to make and use the same, reference being had to the accompanying drawings, and to letters of reference marked thereon, which form a part of this 15 specification.

Figure 1 is an end view of a case for a calculating-machine showing our new design, and Fig. 2 is a front view of the same.

As shown in the drawings, the leading or 20 material feature of our design consists of an annular margin A, giving a beaded effect of ornamentation to the ends of the cylinder b

in front elevation, the said annular margin inclosing, in end elevation, an open-work ornament c, having the general ornamental effect 25 of a conventional vine which surrounds the base of the knob-like protuberance d at the center. At the lower side of the annular end bead the outline of the design is broken by oppositely-concavous lines d' d', extending to 30 the bottom of the calculating-machine case.

The general shape of the body of the calculating-machine case is cylindrical.

What we claim as new is—

The design for a calculating-machine case 35 as herein shown and described.

In testimony that we claim the foregoing we have hereunto set our hands this 15th day of April, 1897.

WILLIAM H. KING.
HERBERT B. TAYLOR.
